UNITED STATES PATENT OFFICE

2,616,192

RAILWAY BALLAST DISPLACING AND
DIGGING MACHINE

Frank H. Philbrick, Evanston, Ill.

Application November 17, 1947, Serial No. 786,367

7 Claims. (Cl. 37—104)

1

The invention relates to machines for digging or displacing ballast from the cribs between the ties of railways.

In ballast digging machines of the drop hammer type in which the displacing tools are mounted on the drop head for loosening the ballast and moving it transversely from the cribs between the ties to the sides of the track, the stresses and impact to which the machine is subjected are increased as the ballast is progressively removed from the cribs when it becomes less effective in checking the drop head and the displacing tools. When the displacing tools are pivotally mounted in the drop head to swing transversely of the track, they change in their angular position as the level of the ballast is lowered and this renders them subject to breaking stresses. Heretofore in machines of the drop hammer type it has been necessary to use shock absorbing or cushioning devices of very heavy, rugged and complex construction to check the movements of the drop head toward the end of each displacing operation.

One object of the invention is to provide a ballast displacing machine of the drop head type in which these shock absorbing or cushioning devices can be eliminated. This object is attained primarily by providing a series of auxiliary picker tools which engage and dig into the ballast in a full adjoining crib and become effective to relieve the machine of the objectionable stresses and impact after a predetermined amount of the ballast has been progressively removed from the crib being cleared. These auxiliary picker tools accomplish useful work in loosening the ballast in a full adjoining crib to expedite its subsequent displacement by the displacing tools and dispenses with the necessity of shock absorbing or cushioning devices.

Another object of the invention is to provide a ballast digging machine of the drop hammer type which operates in an improved manner and simplifies the construction of the machine.

Another object of the invention is to provide means for rendering the auxiliary picker teeth on the drop head inoperative when it is not desired to loosen the ballast in the crib adjoining the one from which the ballast is being displaced.

Other objects will appear from the detailed description.

The invention consists in the several novel features hereinafter described and more particularly pointed out in the claims at the conclusion hereof.

In the drawings:

2

Figure 1 is a transverse section of a machine embodying the invention, taken on line 1—1 of Fig. 3, the drop head being shown in its lowered position;

5 Fig. 2 is a detailed sectional view of one of the lifting chains for the drop head and a coacting abutment on said head;

Fig. 3 is a section taken on line 3—3 of Fig. 1;

10 Fig. 4 is a section taken on line 4—4 of Fig. 3, illustrating one of the picker tools;

Fig. 5 is a transverse section taken on line 5—5 of Fig. 3, the drop head being shown in its raised position;

15 Fig. 6 is a sectional perspective illustrating the guide rollers and tracks for the drop head and a section of the cam and roller for shifting one of the digger tools;

Fig. 7 is a perspective of the cam structure for pivotally shifting the digger tools; and

20 Fig. 8 is a front elevation illustrating mechanism for rendering the picker tools ineffective when desired.

Fig. 9 is a section of one of the air cylinders for lifting the picker tools.

25 The invention is exemplified with a portable frame or truck which is equipped with usual front and rear wheels to travel on the rails of a railway track and is also equipped with a motor and transmission gearing (not shown) for propelling the truck and for providing power for operating the drop head which carries the ballast displacing tools, for example, as exemplified in Patent No. 2,082,594. The frame comprises longitudinal beams 11, cross-connected by transverse beams 12 and 14, upright beams 13, and side-plates 15 rigidly secured together by welding or riveting.

30 A cross-head, generally designated *t*, has mounted thereon the displacing or digging tools as hereinafter described and is supported for vertical strokes to function as a drop head, in an upright guide structure. The cross-head *t* is built up of plates 23 which are rigidly secured together and spaced apart by blocks 24a, and between which the tools for digging and displacing the ballast in the cribs are pivotally mounted.

35 Mechanism for imparting lifting strokes to the head *t* comprises a transverse shaft 24 which is continuously driven from the motor on the truck frame by suitable gearing (not shown) and is journaled in bearing brackets 26 which are supported on cross-beam 14 of the truck frame, a pair of sprocket wheels 30 which are fixed to shaft 24, a pair of idler sprockets 36 on shafts 24' and sprocket chains 33 between sprockets 30

and 36. Intermittent lifting strokes are imparted to head *t* from shaft 24 by rollers 38 which are carried by link chains 33 and are adapted to intermittently engage abutments 39 which are fixed to the head *t*. Each idler sprocket 36 is journaled in a lever 37 which is fulcrumed on the truck frame and is urged to keep its chain taut by a spring 42 applied to the upper end of a rod which is pivoted on one end of said lever. The transversely aligned rollers 38 of chains 33 during their upward travel will engage abutments 39 which are fixed on head *t* and lift it until said rollers ride off said abutments at the end of each up-stroke. The rollers 38 will then release the head *t* for a hammer stroke to the tools carried thereby.

The ballast displacing or digging mechanism carried by the cross-head *t* comprises a series of tools *l*, *l'*, *l''* and *l'''* which are adapted to dig into and displace, during each drop stroke, some of the ballast in a crib transversely to one side of the track and a similar oppositely acting series of tools *m*, *m'*, *m''* and *m'''* which are adapted to displace the remainder of ballast transversely to the other side of the track. The tools *l* and *m* are pivoted at 21 and the remaining tools are pivoted at their upper ends on studs 22 which are supported in the vertically movable head *t*.

The displacing tools are positively and pivotally swung transversely during the drop strokes of head *t* for displacing ballast from the cribs, and as the level of the ballast is lowered the angular movement of the tools is increased. For this purpose tool *l* and tool *m* are each provided with an upstanding arm 55 which has a roller 56 journaled in its upper end. Rollers 56 ride on the straight upper portions of edges of members 48 of the cam structure hereinafter described during the upper portion of the stroke of head *t* and on cams 57 during the lower portions of the strokes of said head for positively swinging the displacing tools outwardly and transversely to displace ballast from the cribs. Tools *l'*, *l''* and *l'''''* are positively shifted by tool *l* and tools *m'*, *m''* and *m'''''* are positively shifted by tool *m*. Tool *l* is provided with a cam or abutment 59 which engages a cam or abutment 60 on tool *l'*; tool *l'* is provided with a cam or abutment 61 which engages a cam or abutment 62 on tool *l''* and tool *l'''''* is provided with an abutment 63 which engages an abutment 64 on tool *l'''''*. These abutments positively swing this series of tools transversely and outwardly so that the lower ends of the tools will, when dropped, dig into the ballast and displace the ballast outwardly from the crib. The oppositely acting set of tools *m*, *m'*, *m''* and *m'''''* are provided with similar abutments for positively swinging this series of tools from a cam 57 and a roller 56 and an arm 55 to displace ballast from a crib to the opposite side of the track. The displacing tools of each set are transversely arranged to progressively displace the ballast from the central portion of the track to one side thereof. Tools *l*, *l'*, and *l''*, *m*, *m'* and *m''* are adapted to work in the crib between the rails to displace the ballast outwardly under the rails. The tools *l'''''* and *m'''''* extend over the rails and to the outer sides thereof respectively for moving the ballast beyond the ends of the ties during the lift of the drop-head. The tools swing inwardly by gravity during their idle up-stroke under control of the tools *l* and *m* which are controlled by arms 55, rollers 56 and cams 57. The lower

end of each of the tools *l'''''* and *m'''''* is also guided by a roller 59 which is mounted in the lower portion of the carrying structure for the drop-head.

5 A structure in which cross-head *t* is mounted includes means for vertically guiding said cross-head and a vertically extending cam structure for pivotally shifting the displacing tools carried by said head. This structure comprises a pair of upright channel-beams *d*, the upper ends of which are rigidly cross-connected by a channel beam *d'*. The cam structure for pivotally shifting the digger tools carried by the head *t* is spaced longitudinally from upright beams *d* to provide a space for the operation of the cross-head *t*, and is built up of side members 48, the upper ends of which are rigidly cross-connected by a channel beam *d''* through plates 49 and spacer bars 50. This cam structure comprises a plate 51 fixedly secured to the lower ends of side members 48 and reinforced by channel beams 52, and connecting members 53, 54 between the side members 48. The lower ends of upright beams *d* and the cam structure are rigidly connected by shoes 41. A bridge plate 45 is rigidly connected to the upper ends of beams *d'* and *d''*. The edges of side members 48 are provided with cam portions 57 for shifting the rollers 56 on the arms 55 which pivotally operate the displacing tools.

30 The cross-head *t* is guided vertically by tracks *f* which are angular in cross-section and are fixedly secured to the inner face of upright beams *d* of the guide structure. Rollers *f'* are journaled between a plate *f''* which forms an upward extension on the cross-head and a bar *f'''* fixed to said plate, and engage the faces *f''* of tracks *f* and confine the cross-head transversely between said tracks. Rollers *f''* are journaled in brackets *f''''* which are fixedly secured to plate *f''*, engage the face *f''* of track *f* and confine the cross-head *t* against forward movement. Rollers *f'''''* are journaled in brackets *f''''''* which are fixed to the cross-head, engage the front face of the side members 48 of the cam structure and confine the cross-head against rearward movement.

35 Shoes 41 on the lower ends of upright guide and cam structure for the cross-head *t* are adapted to engage the railway tracks when the load of the cross-head and the tools carried thereby is imposed upon said structure, the latter being spring-supported on the truck frame to lift the shoes off the railway rails when the load of the cross-head is imposed on the truck frame through the lifting mechanism (chains 33 and rollers 38), so that during the up-strokes of the cross-head, the shoes will be spring-lifted off the rails to permit the machine to be moved along the railway track. For this purpose, vertical rods *e* have their upper ends fixedly secured in brackets *e'* which are fixed to cross beam *d''*, and their lower ends fixed in brackets *e''* which are fixed to cross-beam 52, and are slidably mounted in lower bearings *e''''* and upper bearings *e'''* both of which are fixedly secured to the truck frame. Lift-springs *e''''* are interposed between bearings *e'''*, and adjustable collars *e'''''* on rods *e*. The front side of the structure is also yieldingly supported by coil springs *e''''''* which are interposed between abutments *e''''''* on front channel beam 14 and brackets *e'''''''* which are fixed to the upright beams *d*. Rods *e'''''''* extend through springs *e''''''* and are provided with nuts for limiting the upward movement of the guide and cam structure by said springs.

During the operation of the machine, the springs e^6 , e^8 will lift the guide structure during the up-strokes of the cross-head t while its load is transmitted through the lifting chains to the truck frame. During the drop strokes while the load of head t is imposed on the guide and cam structure through the tool-shifting rollers 56 and cams 57 and friction of the guide rollers on their tracks, said structure will be forced downwardly against the force of springs e^6 and e^8 until the shoes 41 engage and are directly supported on the railway rails a . During the up-strokes of the drop head and the tools, the shoes will be lifted off the railway rails by said springs to permit the truck to be propelled along the railway track for successively digging the ballast from the cribs. When it is desired to transport the machine along the railway track from place to place without operating the cross-head, it is desirable to lift and hold the cam and guide structure of the cross-head for additional clearance between shoes 41 and the railway tracks. For this purpose, a pair of pneumatic rams g are supported on the truck frame and include stems g' which are adapted to engage bridge plates g^2 which are fixed on beams g^3 which are secured to the cross-beams d' and d^2 , for lifting and holding raised the guide and cam structure. When the stems g' are pneumatically raised, they will engage plates g^2 and lift and hold the cam and guide structure to provide the desired clearance between the shoes 41 and the railway tracks.

At the commencement of a displacement operation of tools the crib is filled with ballast and the points of the tools will be retarded thereby. As the drop strokes continue, the ballast will be progressively displaced from the crib and its depth will be increased. When the ballast has been displaced to the desired depth, its resistance in retarding the drop of the head and the tools carried thereby will progressively decrease and the impact of rollers 56 against cams 57 will increase in severity and the angular movement of the tools will increase, which increases the breaking stresses exerted on them. Heretofore, heavy, rugged and complex shock absorbing devices have been used to reduce the severity of the impact blows and decrease the stresses on the tools and other parts. The invention provides a series of auxiliary picker tools which dig into and loosen the ballast in the full crib in advance of the one from which the ballast is displaced. These auxiliary picker tools are mounted on the drop head and are vertically positioned to become effective when the level of the ballast being displaced is lowered to the point where these severe shocks and stresses occur and function near the ends of the drop strokes of the head and tools, to eliminate said shocks and stresses and the necessity of using shock absorbing devices.

These auxiliary tools are mounted to move vertically with the drop head t for lifting and drop strokes therewith and are disposed in longitudinally spaced relation of the truck frame from the displacing tools so they will be in vertical alignment with the crib in advance of the one from which the ballast is being displaced. These auxiliary tools comprise a transverse series of pickers 64 at one side and a similar series of pickers at the other side of the machine. These pickers are mounted on an extension of drop head t so they will be operated vertically and rectilinearly. The points on the lower ends of the pickers are disposed above the horizontal

plane of the lower ends of the displacing tools so that they will not engage the ballast in a filled crib until the displacing tools have been progressively operated to remove the ballast to a depth about 2 to 2½" above the depth of the fully cleared crib. As a result, the pickers will not commence to engage the ballast in the filled crib until some time before the displacing tools drop to the depth at which the crib will be cleared. The displacing tools, in progressively clearing the ballast, will not be retarded or checked by the pickers until they approach a predetermined depth. Thereafter the pickers, during the drop strokes of head t , will encounter the ballast in the filled crib and reduce the impact blows of the drop head and the stresses on the displacing tools until the ballast has been cleared to the desired depth from the crib. These pickers thus function to overcome violent impacts of the drop head on the cam structure and stresses on displacing tools and also loosen the ballast in a full crib to expedite the displacement of the ballast when the machine is advanced into position to displace the ballast from the next succeeding crib.

The upper ends of picking tools 64 are pivotally mounted in a channel bar 65 which is supported by a structural extension on front plate 23 of drop head *t* which comprises plates 66 and angle bars 67 which are welded to the front plate 23 and extension plate *f*² of the drop head *t*. Each tool 64 is pivotally mounted on a pivot shaft 73 which extends through the depending flanges of bar 65 and is provided with a one-way abutment 66a. A coil spring 75 between bar 65 and each picker 64 presses the abutment 66a against said bar and permits the picker to yield laterally to deflect and loosen the ballast during the penetration of the tool into the ballast.

The operation of the machine will be as follows: The truck on which the machine is mounted will be spotted along the railway track so that the displacing tools will be operable in a vertical plane substantially at the center of a filled crib. The pickers will then be positioned in the vertical plane at the center of the crib in advance of the one in which the displacing tools are operative. The drop head *t* will operate the displacing tools and progressively displace the ballast transversely from the crib. At the commencement of a displacing operation, the displacing tools will dig a portion of the top-most ballast and remove it transversely. During the continued operation of the drop head, the displacing tools progressively remove the ballast from the crib and their strokes will be progressively increased as the ballast is removed until the crib has been cleared to the desired depth. During the initial strokes of the displacing tools, the ballast will mainly check the impact blows. As the ballast is progressively displaced, its level will be lowered and the angular movement of the tools will increase. As the level of the ballast is lowered to a predetermined point, the pickers **64** will commence to engage and loosen the ballast in the filled adjoining crib and check the drop head and displacing tools. When the first crib has been cleared of ballast, the machine is advanced to the adjoining crib where the top portion of the ballast has been loosened by the pickers. This loosening of the ballast by the pickers will expedite the removal of the ballast by the displacing tools. Besides effecting this loosening of the ballast in advance of a displacing operation, the resistance of the ballast to the

pickers will reduce the stresses of the drop-head against the carrying and cam structure and the displacing tools during the completion of the displacing operation. This eliminates the necessity of shock-absorbing devices. Thus, the picker tools on the drop head render unnecessary heavy and rugged shock-absorbing or cushioning devices and cause the excess force in the drop head to be utilized for loosening the ballast in the adjoining filled crib for expediting its displacement of the ballast.

During the upper portion of the drop strokes of the head and displacing tools, rollers 56 will ride on the upper straight portions of the cam structure and the ballast initially removed from the crib will check the shocks. During completion of the clearing of the crib, rollers 56 will engage the steep lower portions of the cam surfaces 57 for angular movement of the displacing tools which produce shocks of greater magnitude by the head to the cam structure and truck frame. For this reason, the reduction of the shock toward the completion of a displacing operation is of great importance.

In some repair work, it may be desirable to leave the ballast in adjoining cribs intact. The modified construction illustrated in Fig. 8 exemplifies a construction for rendering the picker tools inoperative. The upper end of each picker tool 64a is pivotally supported by a stud 73a in a channel bar 65a and is normally positioned against one-way fixed stop 74 to permit the pickers to be swung laterally and upwardly in one direction. Oppositely movable rack bars 76 are slidably mounted in channel bar 65a and mesh with gear teeth 77 on series of pickers on opposite sides of the transverse center of the machine. Bell-crank levers 79 are fulcrumed on brackets 80 which are fixed to plates 66 and are pivotally connected to the outer ends of rack bars 76 respectively. Fluid pressure cylinders 82 each contain a piston 87 which is operated in one direction by a spring 88 and in the opposite direction by fluid, such as, compressed air, delivered into one end of the cylinder. A pipe 83 supplies air to cylinders 82 under control of a suitable valve 84 which is connected to a suitable source of air supply and adapted to control the supply of air to and its exhaust from cylinders 82. Pickers 64a are normally and yieldingly held against stops 74 by the pressure of springs 88 transmitted through pistons 87, levers 79 and rack bars 76, to hold the pickers in their operative position. When it is desired to render the picker tools inoperative, valve 84 is manipulated to deliver compressed air into cylinders 82 to shift the pistons 87, levers 79 and racks 76 which will swing the series of pickers in opposite directions and outwardly and upwardly so they will clear the ballast in the filled crib during the drop-strokes of the head t. Springs 88 also permit the pickers 64a to yieldingly swing laterally when they engage the ballast. A bar of wood 89 is interposed between bar 65a and angle bars 67. By substituting bars 89 of different thickness, the penetration of tools 64a relatively to the vertical position of the points of the displacing tools can be varied to time the engagement of the picker tools with the ballast relatively to the displacing tools.

The invention exemplifies a machine of the drop-hammer type for displacing the ballast from cribs between the ties in which the force of the blows transmitted to the guide and frame structure are relieved by utilizing force in the

drop head to loosen the ballast in an adjoining filled crib and which renders unnecessary shock-absorbing devices for cushioning these blows. The invention also exemplifies a machine which provides for selectively rendering the picker tools inoperative when their use is unnecessary. The machine also provides for relative variation of the extent of the penetration of the picker tools to the ballast as the digger tools approach their lower-most position.

The invention is not to be understood as limited to the details set forth since these may be modified within the scope of the appended claims without departing from the spirit and scope of the invention.

Having thus described the invention, what I claim is new and desire to secure by Letters Patent is:

1. In a machine for digging ballast from a railway road bed, the combination of a drop-head, a portable structure for carrying the head, mechanism for imparting lifting strokes to the head, tools mounted on the head for transversely and progressively displacing ballast from a crib and other tools having operative strokes imparted thereto by the head for engaging the ballast in an adjoining crib, after a portion of the ballast has been displaced from said first named crib, and for reducing the transmission of shocks from the head to the carrying structure by the displacing tools.

2. In a machine for digging ballast from a railway road bed, the combination of a portable carrying structure, a vertically reciprocable drop-head operatively mounted in the structure, mechanism for imparting lifting strokes to the drop-head, tools movably mounted on the head for displacing ballast from a crib transversely of the railway track, means for swinging the tools on the head during its down strokes, and pickers mounted on and having operative strokes imparted thereto by the head for loosening the ballast in an adjoining crib, after the displacing tools have removed a portion of the ballast from said first named crib and for reducing the shocks produced by the head to the carrying structure.

3. In a machine for digging ballast from a railway road bed, the combination of a portable carrying structure, a vertically reciprocable drop-head operatively mounted in the structure, mechanism for imparting lifting strokes to the drop-head, ballast displacing tools pivotally mounted on the head to swing transversely of the railway track, means including cam tracks for swinging the tools on the head during its down strokes into a crib, and pickers mounted on and having operative strokes imparted thereto by the head for loosening the ballast in an adjoining crib, after the displacing tools have removed a portion of the ballast from said first named crib and for reducing the shocks produced by the head to the carrying structure.

4. In a machine for digging ballast from a railway road bed, the combination of a portable carrying structure, a vertically reciprocable drop-head mounted in the structure, mechanism for imparting lifting strokes to the head, tools pivotally mounted on the head for transversely displacing ballast from a crib, a rigid extension on the head extending over a tie, and pickers mounted on said extension of the head for vertical movement therewith for loosening the ballast in an adjoining crib, after a portion of the ballast has been removed from said first named crib by the displacing tools, and rollers between the head

and the carrying structure for resisting the off-center thrust on the extension by the engagement of the picker tools with the ballast.

5. In a machine for digging ballast from a railway road bed, the combination of a portable carrying structure, a vertically reciprocable drop-head mounted in the structure, mechanism for imparting lifting strokes to the head, tools pivotally mounted on the head for transversely displacing ballast from a crib, pickers mounted on the head for vertical operative strokes therewith, for loosening the ballast in an adjoining crib, after a portion of the ballast has been removed from said first named crib by the displacing tools, and means for rotatively adjusting the pickers on the head.

6. In a machine for digging ballast from a railway road bed the combination of a portable carrying structure, a vertically reciprocable drop-head mounted in the structure, mechanism for imparting lifting strokes to the head, tools mounted in the head for transversely displacing ballast from a crib, pickers mounted for vertical movement with and pivoted on the head for loosening the ballast in an adjoining crib, after a portion of the ballast has been removed from said first named crib by the displacing tools, and means for selectively swinging the pickers on the head to render them inoperative to engage the ballast in the adjoining crib during the operation of the displacing tools.

10

7. In a machine for digging ballast from a railway road bed, the combination of a portable carrying structure, a vertically reciprocable drop-head operatively mounted in the structure, ballast displacing tools pivotally mounted on the head to swing transversely of the railway track and displace ballast from a crib, cam means for swinging the tools on the head during its down strokes, the angular movement of said tools increasing progressively as the depth of the ballast decreases, and a plurality of pickers mounted on said head, said pickers being operative to loosen the ballast in an adjoining crib and to absorb part of the shock imparted to the carrying structure by the downward strokes of the head only after the ballast from the first crib has been displaced a predetermined amount and the angularity of the movement of the ballast displacing tools has increased to a predetermined degree.
